(57) **CLAIM**

The ornamental design for a power system as shown and described.

DESCRIPTION

FIG. 1 is an isometric view of a power system showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the Figures show portions of the power system that form no part of the claimed design. The broken lines immediately adjacent the shaded areas represent the bounds of the claimed design.

The shade lines in the Figures show contour and do not claim surface ornamentation or treatment.
